STOKER

Otto E. Bornhauser, Sandusky, Ohio, assignor to
The Her-Born Engineering and Manufacturing
Company, Sandusky, Ohio, a corporation

Application July 17, 1933, Serial No. 680,854

1 Claim. (Cl. 110—104)

This invention relates to apparatus for feeding fuel to a fire and for occasioning the distribution of the fuel over the zone of combustion. Particularly, the invention relates to a stoker especially adapted for use in conjunction with large furnaces such as those ordinarily found in power plants, factories, and large apartment or office buildings for heating the boilers of the steam generating systems. However, it is to be understood that my stoker is not limited in its use to the specific application just mentioned, but may be employed in dwellings for attending to the furnace as well.

The aim of this invention is to provide a mechanical stoker by virtue of which a wide spread distribution of fuel is obtained in the combustion zone which insures greater efficiency in the burning of the fuel with a consequent low percentage of waste products of combustion and maximum securing of heat energy. On the other hand, it is also my aim to provide an apparatus that will necessitate a minimum of manual intervention during operation and will have a low upkeep cost, which is an important factor that influences the desirability of the apparatus.

Essentially, the apparatus incorporates a plurality of what I choose to term "fluid fingers" which are, in effect, streams of air or steam that are directed downwardly into the combustion zone from a point offset to one side of the zone. Fuel, which is preferably in the nature of powdered coal or finely divided steam coal, is gravity-fed into the zone of the fluid fingers and onto a deflecting plate having a fuel receiving surface canted downwardly toward the zone of combustion. Hence the fuel falling on the deflecting plate is picked up by the air fingers and ejected into the combustion zone. These fingers are arranged fan-wise to direct the fluid streams to all parts of the combustion chamber and by virtue of the gravity feed of fuel, this device takes the color of a top-fed firing apparatus as distinguished from bottom-fed stokers.

Other objects and advantageous features of this invention are to be observed in the following detailed description and accompanying drawings, wherein like characters of reference indicate like parts, and wherein—

Figure 1 is a fragmentary view of a boiler furnace showing the nature and arrangement of my stoking apparatus with relation thereto, said apparatus being shown in section.

Figure 2 is a fragmentary detail and transverse section of a slightly modified form of blower unit.

Figure 3 is a top plan view of the blower housing unit illustrating the nature and arrangement of the fluid ports.

Figure 4 is a front elevation of the blower unit taken on the line 4—4 of Figure 3.

Figure 5 is a top plan view of a modified form of blower unit.

Figure 6 is a section taken on the line 6—6 of Figure 5.

With reference to the drawings, I have shown my novel stoker as employed in conjunction with a boiler furnace which may be identified as having a front wall A of the usual construction such as fire-brick or other refractory materials. This wall forms one confine of a fire bowl or combustion chamber B having the usual grate bars C in the lower zone thereof which are accessible from the outside through the usual door D.

To accommodate my apparatus, the upper zone of the wall A, shown in Figure 1, is fashioned to provide a downwardly inclined channel 1 that widens in area at its lower end and opens into the combustion chamber. The upper zone of the channel is intended to accommodate a fuel chute 2, hereinafter referred to, whereas the lower zone 25 is intended to accommodate what I choose to term the "blower unit" of my apparatus. The fluid supply pipe 3 is also brought in through the end wall of the furnace and is threaded into the blower unit as will be hereinafter referred to. 30

As shown in Figure 1, my novel blower unit is shown as comprising a body portion 4 which preferably takes the shape shown in Figures 3 and 4. This body portion is further provided with an interior chamber 5 adapted to receive a fluid such as steam or compressed air through the port 6 which communicates with a source of fluid supply through the pipe 3 which is valved as at 7 to control the passage of fluid thereto.

As hereinbefore stated, it is my intention to feed the fuel by gravity to the blower unit and to deflect the fuel from its original path of travel into the combustion zone B of the furnace. To accomplish this, I provide on the blower unit, surfaces that will serve to direct and guide the stream of fuel in conjunction with the fluid blast for forcibly ejecting the said fuel to the fire bowl. To this end I have provided a plurality of ports 8, as best shown in Figure 3, that communicate with the chamber 5 and are directed outwardly over a spade-shaped deflecting member 9, Figures 1, 3, and 4, that is formed as an integral part of the housing and extends outwardly therefrom. These ports 8 are arranged as radii about a common center 10, Figure 3, and tend to direct a scavenging 55

fluid flow over the top surface of the member 9 to blow off the particles of fuel that may be deposited thereon.

The blower unit is additionally provided with a surface 11 that overlies the ports 8 and is angularly disposed with relation thereto and with relation to the deflecting member 9. Surface 11 is a substantial extension of the bottom surface of the chute 2 to present an inclined path over which the fuel may freely travel into the zone of the air fingers. To accommodate the lower end of the chute 2, the surface of the unit is offset inwardly to provide a niche 12 against which the lower end abuts.

In Figure 2, the blower unit is of generally the same construction as hereinbefore described with relation to Figures 1, 3, and 4, excepting that the base or bottom wall of the niche or recess 12a has a slightly different angular relation to surface 11a, as compared with the corresponding elements 12 and 11 respectively, in Figures 1 and 3. For convenience, the elements of the Figure 2 unit which are similar to the elements of the unit of Figures 1, 3, and 4, are designated by the same reference characters with the exponent *a*. The mounting of the modified blower unit of Figure 2 in the furnace is more particularly referred to herein-after.

Assuming now that the furnace wall A has been properly formed to receive the various parts of this apparatus, the blower unit may be placed therein in the position shown in Figure 1 with the forward end of the member 9 lying on the bottom of the channel 1. The rear end of the unit is elevated through engagement with one of the fire brick as shown so that approximately a straight path is afforded to the fuel in a downwardly angling direction toward the zone of the fluid fingers. When the valve 7 is open, air or steam under pressure flows through the ports 8 and outwardly over the surface of the member 9 which is thereby scavenged of all the fuel being deposited thereon which is in turn blown over into the combustion chamber where it is consumed. In this manner the fuel will be afforded a wide spread distribution over the combustion zone with consequent increase in efficiency in the burning thereof.

In some types of furnace the relation between the combustion chamber and the fuel feed inlet is such that the blower unit would not operate advantageously if placed in a position shown in Figure 1, and accordingly, the blower may be placed on the floor of the channel in the position shown in Figure 2. Now this positioning of the blower unit occasions a slight rearrangement in the support for the lower end of the chute 2a in this manner, the upstanding wall of the niche 12a is substantially normal to the surface 11a and the bottom surface of the niche is substantially parallel to the surface 11a, although in a lower plane, so that the lower end of the chute will seat properly and firmly in engagement with the cooperating surfaces on the blower. Hence, a substantially straight path is afforded from the point of entry of fuel into the discharge chute 2a to the surface of the plate 9a whereas, in Figure 1 there is a slight angle in the path, in the zone of the blower. Accordingly, when the blower unit rests on the bottom of the channel 1, the deflecting surface 9a, instead of being downwardly canted into the zone of combustion, lies substantially normal to the vertical axis of the combustion chamber. The fuel will be efficiently discharged, nevertheless, by virtue of the fluid blast from the ports 8a.

In Figure 5, I have shown a slightly modified form of blower unit that is intended to overcome a certain feature, which cannot be termed objectionable, but which, for some reason or other, might not appeal to engineers. By this I mean that the fuel traversing the chute may have a tendency to pile up on the deflecting plate 9b in certain zones between the air fingers. To overcome this, the modification as shown at Figure 5 is produced with a plurality of ridges 20 that project upwardly from the spade-shaped deflecting member 9b, lying in spaced relation and extending from the marginal confine of the plate rearwardly to the body portion of the blower. It is to be observed that these ridges terminate, at their inner ends, between the air ports 8b so that, in effect, each air port is directed into a channel formed by two spaced ridges and a floor portion 21, Figure 6, inclined to the horizontal, as shown. In this way, all material falling on the plate and seeking out the bottom-most level of the floor 21 will be in substantial alignment with the fluid flow and the piling up of fuel will be overcome.

It is also to be observed that these ridges are slightly curved in the direction of their length toward the outer marginal edges of the spade-shaped plate 9b on either side of the longitudinal center line of the device. Hence, with the arrangement just detailed, I will afford a complete scavenging of the surface of the plate 9b receiving fuel, viz; surfaces between the ridges and the surfaces between the outermost ridges and the marginal edges of the plate, which are also inclined toward the center of the plate as shown in Figure 6. In all other respects this blower unit is identical with the unit shown in Figures 1 and 2 and is intended for installation wherever such blower units may be installed.

It is to be observed that I am able to vary the rate at which fuel is fed to the combustion chamber by virtue of the hand valve 7 which controls the fluid under pressure, and by the same token to vary the feeding of the fuel to the zone of combustion. It is a known fact that a blower will create a forced draught to thereby accelerate the rate of combustion. It may therefore be said that I provide a means in the form of the hand valve 7 for varying the rate of combustion as well as the rate of feed. It may be further stated that I vary the distribution of the fuel as well as the rate of combustion. This is extremely advantageous since I reduce the necessity for manual intervention in controlling the rate of feed, the distribution of the fuel, and the rate of combustion, all from a single source.

Having thus described my invention, what I claim as new and desire to secure by Letters Patent of the United States, is—

In a stoking device of the class described, a unitary fuel guide and distributor comprising a hollow body, the upper surface of which presents an inclined fuel receiving and guiding area of substantial extent and over which fuel deposited thereon directly passes by the action of gravity, said upper surface being provided with a fuel chute receiving recess having a forward wall constituting an abutment shoulder for engagement with the rear end of the chute to support the latter, and a bottom wall defining the angle of disposition of the fuel chute in its cooperation with the guide and distributor unit in directing fuel to the latter by gravity, said hollow body defining within the same a fluid chamber, and having a fluid inlet passage and outlet passages communicating with said chamber, said

outlet passages extending through the walls of said body adjacent the lower portion of the fuel receiving and guiding area aforesaid, said body being further provided with an integral plate extending rearward therefrom and having a surface of substantial area serving to receive fuel from said aforementioned inclined surface in ad-

vance of said fluid outlet ports and from which latter surface fuel deposited thereon is discharged into the combustion chamber of a furnace by a fluid medium directed into the fluid chamber under pressure.
